UNITED STATES PATENT OFFICE

ORRIN C. KNEEDLER, OF LEBANON, MISSOURI
CONCRETE ROAD CENTER STRIPING MACHINE

Application filed November 6, 1929. Serial No. 405,187.

The present invention relates to a machine for striping with tar the center of a concrete road, pavement, or the like and has for its prime object to provide a wheeled apparatus which may be pushed along and will drop the tar into the crack and a broom followed along properly spreading the tar so that the operation is capable of being accomplished continuously by a single person in an easy and expeditious manner.

A still further very important object of the invention resides in the provision of a machine of this nature which may be manufactured at a low cost and simple in its construction, strong and durable, and thoroughly efficient and reliable in use and operation.

With the above and numerous other objects in view as will appear as the description proceeds, the invention resides in certain novel features of construction, and in the combination and arrangement of parts as will be hereinafter more fully described and claimed.

In the drawings:
25 Figure 1 is a side elevation of the machine showing the wheel frame in section,

Figure 2 is a top plan view of the wheeled frame,

Figure 3 is a vertical transverse section therethrough taken substantially on the line 3—3 of Figure 2 looking forwardly,

Figure 4 is a similar section taken substantially on the line 4—4 of Figure 2 looking rearwardly,

35 Figure 5 is a detail sectional view through the tar can showing the valve construction, and

Figure 6 is a detail section taken substantially on the line 6—6 of Figure 1.

40 Referring to the drawings in detail it will be seen that the numeral 5 denotes a rectangular frame from intermediate portions of the sides of which depend brackets 6 having an axle 7 mounted thereon and wheels 8 are journaled on this axle.

An angle iron 9 is mounted on the front rail of the frame. A cross bar 10 is attached to rear portions of the side rails of the frame and the center has a downwardly offset portion forming a pocket 11. A bail 12 is at-

tached by suitable plates to forward portions of the side rails of the frame and has an elongated handle 14 extending from the rear portion thereof and said rear portion is held at an elevation by means of suitable upright brackets 15 so that the handle 14 inclines upwardly and rearwardly in a convenient manner.

55 A U-bolt 16 anchors to the center of the rear rail of the frame 5 a broom handle 17 so that broom 18 depends downwardly therefrom to engage the road or pavement.

60 A tar tank 19 has the usual spout 20 so that it is capable of being used in the usual well known manner if desired and is formed on its rear side near the bottom with a pipe section 21 resting in the pocket 11 while the front bottom of the can rests on the angle iron 9.

65 A valve structure V is associated with the pipe section 21 comprising an elongated vertical casing 23 with a reciprocable stem 24 therein having a passage 25 at the lower end thereof which may be brought into registry with the bore of the pipe 21 for permitting the 70 passage of the hot tar therethrough down into the crack of the roadway or pavement.

75 A handle 26 is provided at the top of the stem 24 so that the valve may be turned on and off conveniently.

80 From the above detailed description it will be seen that this machine may be pushed along by and opening the valve the tar will flow down into the crack and the broom will follow and properly spread and smooth the 85 tar in the crack all in one continuous operation.

85 It is thought that the construction, operation, utility and advantages of this invention will now be quite apparent to those skilled in this art without a more detailed description thereof.

90 The present embodiment of the invention has been disclosed in considerable detail merely for the purposes of exemplification since in actual practice it attains the features of advantage enumerated as desirable in the statement of the invention and the above description.

95 It will be apparent that changes in the de- 100

tails of construction, in the combination and arrangement of parts may be resorted to without departing from the spirit or scope of the invention as hereinafter claimed or sacrificing any of its advantages.

Having thus described my invention, what I claim as new is:

1. A machine of the class described comprising a substantially rectangular frame, an axle journalled in brackets and carrying wheels on the ends thereof, said brackets being placed slightly forward of the center of the frame, a U-bolt having its ends through the rear of the frame, a short handled broom maintained by the bolt in ground sweeping position, and a U-shaped bail having inturned portions on its ends pivoted in the frame forward of the axle, a pole handle extending from the bight portion of the bail, and a pair of uprights depending from the bail and adapted to rest upon the rear side portions of the frame for supporting the bail and handle at an upward and rearward inclination, and a cylindrical valved dispensing marking fluid receptacle removably mounted within the frame and adapted to rest on cross bars mounted at the lower side of the frame.
2. A machine of the class described comprising a substantially rectangular frame, a bracket secured to the underside of each side member of the frame, an axle journalled through the brackets carrying wheels on the ends thereof, said brackets being placed slightly forward of the center of the frame, a U-bolt having its ends through the rear member of the frame and its bight embracing and securing the handle of a striping broom and maintaining it in ground sweeping position, a U-shaped bail having inturned portions on their ends pivoted on the frame forward of the brackets, a pole handle extending from the bight portion of the bail, and a pair of uprights depending from the rear side portions of the bail to contact the frame for supporting the bail and handle at an upward and rearward inclination, and a removable valved dispensing marking fluid receptacle removably mounted within the frame and resting on an angle iron and a cross bar supported across the lower edge of the frame, said receptacle comprising a spouted watering-pot structure, and a tube projected rearwardly from the rear wall of the receptacle near the bottom thereof and in communication with the interior of the receptacle, a cylinder rising on the outer end of the tube and spaced parallel with the pot, a rod having an operating handle turnable in the cylinder to close the outer end of the tube.
3. A road striping device of the character described comprising a rectangular frame having an axle with wheels supporting the frame forward of its center, a pair of longitudinally spaced cross members at the under- side of the frame, the front cross member be-

ing elevated above the rear cross member, a striping brush secured upon the back of the rear of the frame, a bailed handle pivoted to the sides of the frame forward of the axle to support the handle at an angle, a removable spout bucket supportable on said cross members and within the sides of the frame in backward tilted manner, a tube projecting from the bottom of the rear wall of the bucket, a vertical cylinder carried in spaced manner on the bucket and communicating with said tube, and a handled rotatable valve rod in said cylinder adapted to cooperate with said tube to control the flow of a fluid from the bucket.

In testimony whereof I affix my signature.

ORRIN C. KNEEDLER.
